APPARATUS FOR CLEANING THE SCREEN
IN A WELL

Myron Macy Kinley, Tulsa, Okla.

Application February 20, 1935, Serial No. 7,368

13 Claims. (Cl. 166—20)

This invention relates to a method of and apparatus for cleaning the screen in a well of accumulations tending to block flow of fluid therethrough. For example, in certain oil wells, 5 the fluid producing formation is so soft and crumbly that the oil exuding therefrom carries with it large quantities of the material. Since this material is very abrasive in character and destructive to the pumping apparatus, various 10 types of screens are employed to exclude its entry into the pumping system. The excluded material, therefore, accumulates on the outer side of the screens and blocks flow of the fluid. When this occurs, it has heretofore been found 15 more practicable to replace the screen with a new one, which results in a very expensive operation.

It is, therefore, one of the principal objects of the present invention to provide means whereby such screens may be cleaned in place at a minimum of trouble and expense with the result that the efficiency of the screen is restored to approximately its original flow capacity.

In accomplishing this and other objects of the 25 invention, hereinafter pointed out, I have provided improved details of structure, the preferred form of which is illustrated in the accompanying drawings, wherein:

Fig. 1 is a vertical section of the bottom of a 30 well in which is lowered a screen cleaning apparatus embodying the features of the present invention.

Fig. 2 is an enlarged vertical section through the well and cleaning apparatus.

Fig. 3 is an enlarged section illustrating the 35 step of igniting the explosive charge.

Fig. 4 is a similar view illustrating movement of the piston under the propelling force of the explosion to force fluid reversely through the 40 apertures of the screen.

Fig. 5 is a detail vertical section through the firing portion of the apparatus, particularly illustrating the method of sealing the breech thereof.

Fig. 6 is a horizontal section on the line 6—6, 45 Fig. 2.

Fig. 7 is a section on the line 7—7, Fig. 2, particularly illustrating the nozzle from which fluid is forced under pressure through the apertures of the screen.

Referring more in detail to the drawings:

1 designates the bore hole of a well which extends from the surface of the earth into a fluid producing formation 2, for example, an oil sand, 55 from which oil flows into the oil pocket 3 at the

bottom of the hole. The bore hole 1 is encased by a casing 4 supported within the well and extending to the bottom of the pocket 3, and in which is inserted a section 5 having a plurality of relatively large perforations 6 through which oil flows into the casing.

As above pointed out, the oil producing formation 2 is mainly sand and is so soft that it crumbles and becomes intermixed with exuding oil. The apertured section of the casing is therefore provided with a form of exterior screen 7 sleeved thereover and having a plurality of openings 8 of sufficient size to exclude the intermixed material from the oil entering the casing through the perforations 6.

When the well is initially "brought in" there may be sufficient formation pressure to cause natural flow of oil through the casing; however, in most oil sands, the formation pressure gradually recedes until it is not sufficient to cause 20 flow from the well and some form of mechanical pumping apparatus must be used and it is for the purpose of protecting the pumping apparatus that the screen 7 has been inserted over the well casing. Otherwise, the crumbling material would be destructive to the working parts of the pumping apparatus. After such a well has been in operation, the excluded material builds up around the screen 7 to block the free entry of oil into the casing, resulting in a greatly diminished flow.

As above pointed out, it is the object of the present invention to provide for cleaning the screen of accumulated material in such a manner that it is not necessary to remove the casing 35 or screen from the well. This is accomplished by creating a reverse flow of fluid through the apertures of the screen under the propelling force of an explosive charge, as now to be described.

9 designates a cleaning apparatus constructed 40 in accordance with the present invention and which includes a cylindrical body 10 of suitable diameter to be freely lowered within the casing 4. In the illustrated instance the body is made up of a cylinder section 11, a nozzle 12, a guide section 13, and a firing head 14.

The cylinder section 11 is constructed of relatively heavy material and has an inner bore extending axially thereof to provide a piston and firing chamber 15 of a length to retain sufficient 50 fluid 16 for flushing the screen as later described. The lower end of the cylinder is externally threaded as at 17 to engage the internal threads 18 formed in the upper end of the nozzle 12.

The nozzle 12 includes a cylindrical body of 55

larger diameter than the section 11 so that the periphery 19 thereof extends in relatively close relation with the inner wall of the casing 4 and is provided with an axial bore 20 forming a continuation of the piston chamber 15. Formed in the wall 21 thereof is a plurality of radial slots 22 from which the fluid 16 is ejected through the screen as later described. The bore 20 extends below the lower ends of the slots and is slightly enlarged in diameter to provide a check chamber 23 for checking and stopping movement of the piston 24 when it reaches the bottom end of the nozzle. The lower end of the nozzle is preferably rounded as at 25 and is provided with an internally threaded socket 26 for threadedly connecting the upper end of a rod 27 which is adapted to support the apparatus in cleaning position within the well.

The upper end of the section 11 is internally threaded as at 28 to receive the external threads 29 of the firing head by which the guide section 13 is attached to the section 11, and which houses a portion of the firing mechanism.

The firing head member 14 includes a central portion 31 of substantially the same diameter as the exterior diameter of the cylinder and oppositely extending connecting portions 32 and 33 conforming in diameter to the chamber 15 and the inner diameter of the guide section 13 respectively. The portion 32 carries the threads 29 and forms with the central portion 31 an annular shoulder 34 tightly engaging the upper end 35 of the section 11 to seal the upper end of the chamber 15 against leakage. The portion 33 is externally threaded as at 36 to engage the internal threads 37 on the lower end of the guide section 13 and also forms an annular shoulder 38 to seat the lower end of the guide section as clearly shown in Fig. 3.

The guide section 13 includes a pipe 39 having an outer diameter corresponding to the outer diameter of the section 11 and the upper end thereof has a closed top 40 provided with an axial opening 41 for passing a suspension cable 42 by which the apparatus is lowered into the well. The opposite sides of the guide section have slotted openings 43 to provide free movement of the well fluid therethrough upon actuation of a weight 44 later described.

Extending axially through the firing head 14 is a bore 45 of substantially smaller diameter than the chamber 15 to slidably mount a firing pin 46 and house a primer 47 which is retained by a plug 48 that is threaded into the lower end of the bore as at 49 and has a protruding portion 50 projecting within a powder chamber 52 formed within the piston 24, the plug 48 being provided with an axial fire emitting opening 51 through which fire from the primer is directed into the powder chamber.

The upper end of the piston 24 has an inwardly and downwardly tapered annular rim 53 for engaging against a correspondingly tapered seat 54 that is provided on the lower face of the connecting portion 32 of the firing head 14 so that when the piston is in its uppermost position and engaging the seat 54, the inclined surfaces will help to maintain a gas tight seal between the piston and the coupling member.

The firing mechanism includes the firing pin 46 which comprises a cylindrical bar freely slidable within the bore 45 and has a flattened upper end 55 and a cone-shaped lower end 56 to engage respectively against a sealing disk 57 and a fulminating cap 58 on the primer 47. The sealing disk 57 is preferably formed of soft metal

and is inserted in an internally threaded socket 59 to be engaged firmly between the seat 60 and the bottom end of a plunger guide member 61. The firing pin 46 is of sufficient length so that the upper end thereof normally contacts the lower face of the disk as shown in Fig. 5. The plunger guide member 61 has its lower end threaded into the socket 59 and its upper end projecting within the guide section 13. The plunger guide member has an axial bore 62 terminating at its lower end in a socket 63 for accommodating a plunger 64. The plunger 64 includes a shank 65 that is slidable in the bore 62 and a head 66 movable within the socket 63 to puncture the sealing disk 57 upon actuation of the weight.

The upper end of the firing pin projects from the guide and is normally protected against accidental operation of the weight by a bushing 67 that is threaded in a socket 68 formed in the upper end of the guide and which is provided with a head portion 69 by which it is rotated about the firing pin to move it into the threaded socket for exposing the end of the firing pin to the action of the weight 44.

In order to seal the breech portion of the firing mechanism after piercing of the sealing disk, the head of the firing pin includes a cone-shaped collar 70 spaced from the end thereof and having a flattened annular face 71 to seat against the bottom 72 of the socket 63 under pressure of gas generated in the powder chamber, as later described. The weight 44 includes a heavy body of metal of cylindrical shape to slide freely within the guide section and which has a neck on its upper end in which the end of the cable is babbitted or otherwise attached as illustrated at 73, Fig. 2.

In using an apparatus constructed as described for cleaning a well screen, the pumping apparatus 40 is first removed from the well. The cleaning apparatus is then assembled and prepared for firing by inserting the firing pin 46 within the bore of the firing head 14. The primer 47 is then inserted within the lower end of the bore and retained by the plug 48. The sealing disk 57 is then inserted in the threaded socket 59 of the coupler to seat against the shoulder 60.

The plunger 64 is then sleeved within its guide 61 so that the head thereof is retained within the recess 63 and the guide is threaded into the firing head in sealing contact with the disk 57. The bushing 67 is then threaded into the socket of the guide to protect the upper end of the plunger against accidental discharge of the primer.

The section 11 is threaded on the firing head 14 after which the chamber 52 is filled with an explosive and the piston inserted in the lower end of the cylinder to seat against the tapered seat 54 of the firing head 14. To retain the piston in this position a plurality of sealing disks 74 are then inserted through the bottom end of the cylinder and moved into engagement with the lower face of the piston after which the peripheries thereof are caulked against the wall of the firing chamber to provide a liquid tight seal and prevent entrance of liquid past the piston into the powder chamber.

With the parts assembled as described, it is obvious that the powder chamber is sealed from below by the disks 74 and from above by the disk 57. The nozzle 12 is then threaded on the lower end of the section 11, after which the guide section 13 carrying the weight 44 is threaded on the upper end of the firing head. A rod 27 is 75

then threaded into the lower end of the nozzle which is of sufficient length to support the nozzle at the upper end of the screen when the lower end of the rod engages the bottom of the well. The bushing 37 is then adjusted to expose the projecting end of the plunger.

The apparatus is then lowered within the casing until it is stopped by the rod 27 engaging with the bottom of the well. Upon entering the well fluid, the nozzle and piston chamber are filled with well fluid which is admitted thereto through the slots 22. During lowering of the apparatus into the well, the weight 44 is retained in the upper end of the guide section, but when the rod 27 engages the bottom of the well, downward movement of the apparatus is stopped to free the weight 44 so that a quick release on the tension of the cable results in striking of the weight against the plunger 64 driving the end thereof through the sealing disk 57 and the firing pin against the fulminating cap of the primer, igniting the primer and causing fire to be directed through the bore of the plug 48 into the powder chamber of the piston to ignite the powder and generate sufficient gas to drive the piston 24 with great force toward the check chamber 23 in the lower end of the nozzle.

Movement of the piston 24 forces the fluid in the piston chamber 15 thereahead and squirts it out through the slots 22 of the nozzle and through the apertures of the screen to break up the material clinging to the outer surface thereof and which is blocking the apertures therein.

After the upper end of the piston has moved past the upper portion of the slots 22, the gas which has been generated is free to escape through the slots of the nozzle to supplement the action of the fluid in cleaning the screen.

In the meantime the plunger 64 is forced back so that the collar thereon engages the seat 72 thereby preventing escape of the combustion pressure through the breech of the apparatus.

When the lower end of the piston enters the check chamber 23, fluid is trapped therein to check any destructive force of the piston so that it does not injure the apparatus and the apparatus can be again used by reloading the piston and inserting a new primer as previously described. Attention is directed to the arrangement of the nozzle ports so that when the piston has come to rest the piston has passed the upper portion of the ports, whereby the fluid rushes back into the tubular body on the opposite side of the piston causing a reverse flow through the screen.

After firing, the apparatus is removed from the well, reloaded, and a shorter rod 27 applied to the end of the nozzle. The apparatus is then relowered into the well and fired in the manner as above described to clean the portion of the screen below that cleaned in the previous operation.

The firing operations are continued until the nozzle has reached the lower end of the screen, whereupon the entire length of the screen has been cleaned of the clogging material and the oil is again free to flow through all the apertures in the casing.

Attention is directed to the fact that suddenness of the shot, or rather the sudden force of the fluid at high velocity, through the slots of the nozzle is an important factor in obtaining efficient results.

From the foregoing, it is obvious that I have provided an apparatus which permits cleaning of

the screen directly within a well so that it is not necessary to remove the screen as has been the customary practice.

What I claim and desire to secure by Letters Patent is:

1. An apparatus for cleaning the inlets in a well tubing of accumulations tending to block flow of fluid including means for lowering an explosive charge through the tubing into proximity of the inlets, means for exploding said charge, 10 means for confining a body of fluid, a piston movable in said confining means under force of the explosion to discharge said fluid, means for directing streams of the fluid under movement of the piston in opposition to the natural flow of 15 fluid through the inlets, and means for checking movement of the piston after discharge of the fluid.

2. An apparatus for removing the material clogging the inlet opening of a well tubing including a body member having a firing chamber, a nozzle connected with the body member, means in the body member for supporting an explosive charge, a piston in the firing chamber movable in the direction of the nozzle responsive to explosion of said charge, and means for firing the explosive charge to effect operation of the piston. 20

3. An apparatus for removing the material clogging the inlet opening of a well tubing including a body member having a firing chamber, 30 a nozzle connected with the body member, a piston reciprocable in the firing chamber in the direction of said nozzle and having a pocket for containing an explosive charge, and means for exploding the charge for actuating the piston. 35

4. An apparatus for removing the material clogging the inlet opening of a well tubing including a body member having a firing liquid containing chamber, a nozzle connected with the body member, means in the body member for supporting an explosive charge, a piston in the firing chamber movable in the direction of the nozzle responsive to explosion of said charge to force liquid from said chamber through the nozzle, and means for firing the explosive charge to 45 effect operation of the piston.

5. An apparatus of the character described including a body member having a firing chamber, a nozzle connected with the body member, a piston reciprocable in the firing chamber in the 50 direction of said nozzle and having a pocket for containing an explosive charge, a firing head connected with said member, a primer in the firing head, a firing pin mounted in the head for discharging the primer to explode said charge, 55 and means slidably carried by the body member for actuating the firing pin.

6. An apparatus of the character described including a body member having a firing chamber, a nozzle connected with the body member, a piston reciprocable in the firing chamber in the 60 direction of said nozzle and having a pocket for containing an explosive charge, a firing head connected with said member and having seating contact with the piston, a primer in the firing 65 head, a firing pin mounted in the head for discharging the primer to explode said charge, and means slidably carried by the body member for actuating the firing pin.

7. An apparatus of the character described including a body member having a firing chamber, a nozzle connected with the body member, a piston reciprocable in the firing chamber in the direction of said nozzle and having a pocket for containing an explosive charge, a firing head 70

connected with said member having a bore communicating with said pocket, a primer in said bore, a firing pin mounted in the bore for discharging the primer to explode said charge, sealing means for closing said bore of the firing head, a plunger acting against said sealing means to effect actuation of the firing pin, and means for operating said plunger.

8. An apparatus of the character described including a body member having a firing chamber, a nozzle connected with the body member, a piston reciprocable in the firing chamber in the direction of said nozzle and having a pocket for containing an explosive charge, a firing head connected with said member and having a bore communicating with said pocket, a primer in the firing head, a firing pin mounted in the bore of the head for discharging the primer to explode said charge, puncturable sealing means for closing said bore of the firing head, puncturing means acting against said sealing means, means for reciprocating the puncturing means to effect actuation of the firing pin through said sealing means, and means on the firing pin responsive to explosion of said charge for reestablishing seal of the bore.

9. An apparatus of the character described including a body member having a firing chamber, a nozzle connected with the body member, a piston reciprocable in the firing chamber in the direction of said nozzle and having a pocket for containing an explosive charge and having a tapered seat encircling said pocket, a firing head connected with said member and having a bore communicating with said pocket and having a seat for said piston to seal the pocket, a primer in the firing head, a firing pin mounted in the head for discharging the primer to explode said charge, sealing means closing said bore of the firing head, and means for actuating the firing pin including means for puncturing the sealing means.

10. An apparatus of the character described including a body member having a firing chamber, a nozzle connected with the body member, a piston reciprocable in the firing chamber in the direction of said nozzle and having a pocket for containing an explosive charge, a firing head connected with said member and having a bore, a primer in said bore, a plug in the bore to retain the primer and having a firing port open-

ing to said pocket, a firing pin mounted in the head for discharging the primer to explode said charge, puncturable sealing means for closing said bore of the firing head at the end opposite said plug, puncturing means acting against said sealing means to effect actuation of the firing pin, means for operating said puncturing means, and means on the firing pin responsive to explosion of said charge for reestablishing seal of the bore.

11. An apparatus for removing material clogging the inlet openings of a well tubing including a tubular body member for containing a liquid, a nozzle connected to the tubular body member and having lateral ports arranged for discharging the liquid laterally through the inlet openings of the tubing, a piston slideable in the tubular body member, and means for reciprocating the piston to hydraulically discharge the liquid through said ports and through the inlet openings of the tubing, said piston being movable past a portion of said ports whereby fluid rushes into the tubular body on the opposite side of said piston.

12. An apparatus for removing material clogging the inlet openings of a well tubing including a tubular body member for containing a liquid, a nozzle connected to the tubular body member and having lateral ports arranged for discharging the liquid laterally through the inlet openings of the tubing, a piston slideable in the tubular body member, and means in the tubular body member for effecting an explosive charge against the piston to propel the piston in the direction of the nozzle for hydraulically discharging the liquid through said ports.

13. An apparatus for removing material clogging the inlet openings of a well tubing including a tubular body member for containing a liquid, a nozzle connected to the tubular body member and having lateral ports arranged for discharging the liquid laterally through the inlet openings of the tubing, a piston slideable in the tubular body member, means in the tubular body member for effecting an explosive charge against the piston to propel the piston in the direction of the nozzle for hydraulically discharging the liquid through said ports, and means in the nozzle for checking the piston.

MYRON MACY KINLEY.
